UNITED STATES PATENT OFFICE.

WILLIAM R. FOWLER, OF PHILADELPHIA, PENNSYLVANIA, ASSIGNOR TO
LEWIS J. MYERS, OF SAME PLACE.

ROPE RAILWAY.

SPECIFICATION forming part of Letters Patent No. 330,106, dated November 10, 1885.

Application filed September 7, 1885. Serial No. 176,363. (No model.)

To all whom it may concern:

Be it known that I, WILLIAM R. FOWLER, a citizen of the United States, residing in Philadelphia, Pennsylvania, have invented certain 5 Improvements in Rope Railways, of which the following is a specification.

My invention relates to that class of wire-rope railways in which the receptacle is hung upon the moving rope and is carried along by 10 frictional contact therewith, an instance of such a railway being shown in British Patent No. 2,281 of 1868.

My invention consists of certain details in the construction of such a rope railway with 15 the view of lessening the wear of the parts, reducing noise, insuring steadiness in running, and preventing the accidental release of the receptacle from the rope.

In the accompanying drawings, Figure 1 is 20 a diagram showing a system of endless-rope railway constructed in accordance with my invention; Fig. 2, a side view of the driving-pulley and its hanger, with part of the rope and a supporting-wheel therefor; Fig. 3, a side 25 view of the take-up and carrier pulley at the outer end of the rope, with one of the receptacles; Fig. 4, a side view of one of the brackets for the supporting-pulleys, with one of the receptacles in end view; Fig. 5, a plan view 30 of the take-up and carrier pulley and devices connected therewith; Fig. 6, a perspective view of part of one of the receptacles; Figs. 7 and 8, enlarged views of parts of the wheels employed; Figs. 9 and 10, diagrams showing 35 the method of changing the course of the rope; Fig. 11, a diagram showing a duplex driving system, and Fig. 12 a view showing a modification of the invention.

It may be stated at the outset that, while my 40 invention is applicable to rope railways for various purposes, it has been devised especially for use in stores for the purpose of carrying parcels and cash from the counters to a central compartment, where the cash is received and the parcel wrapped up, the wrapped parcel, with the change, if any, being then returned to the counter from which it was sent.

In Fig. 1 I have shown a diagram of a system in accordance with my invention, A being 45 a driving-pulley at the central station, this

pulley being grooved for the reception of a series of endless belts, *a*, four being shown in the present instance, which belts are carried at the outer ends by suitable pulleys, *B*, so 55 that each belt forms a conveyer from a counter to the central station and from said station back to the counter.

The driving-pulley *A* (shown in Fig. 2) is secured to a shaft, *D*, adapted to bearings in a 60 frame, *E*, and provided with a belt-pulley, *F*, which may be located adjacent to the driving-pulley, as shown, or may be in the room or apartment above or below that in which the pulley *A* is located, as convenience may suggest. Each of the carrying-pulleys *B* at the outer end of the line turns on a pin, *g*, carried by a yoke, *G*, to which is connected one end of a coiled spring, *i*, the other end of the latter being connected to a rope or chain, *d*, which 70 is wound upon the barrel of a windlass, *J*, the shaft of the latter being adapted to bearings in a bracket, *H*, and being squared at one end for the reception of a suitable wrench or handle, whereby the cord *d* may be wound upon 75 the barrel of the windlass, and tension thus imparted to the endless rope *a*; a pivoted pawl, *h*, being adapted to a ratchet-wheel, *k*, on the windlass, so as to prevent the unwinding of the rope from the latter. The yoke *G* 80 might be connected directly to the rope *d*; but the use of the spring *i* is preferred, as tending to prevent excessive strain upon the endless rope *a* by the action of the windlass. The yoke *G* has opposite projecting arms, *f*, each 85 carrying grooved wheels *I* for the reception and support of the rope *a* at points adjacent to the pulley *B*, and at suitable intervals along the line said rope *a* is supported by similar pulleys *I*, hung to brackets *L*, which are secured to any available support in the room or apartment in which the line is erected. 90

The receptacle in which the load is to be conveyed consists in the present instance of an open basket, *M*, having near each end a frame, *N*, these frames being properly stayed by longitudinal rods *m*, and each frame carrying at the upper end a grooved wheel, *P*. Each of the frames is open at one side, so that the receptacle can be adjusted to such position that 95 the wheels *P* are directly above the rope *a*, the receptacle being then lowered until the 100

wheels rest upon the rope, when the forward movement of the receptacle will be dependent upon the frictional contact of the wheels *P* with the rope.

5 When the receptacle is first hung upon the rope, the wheels *P* will be rotated; but as the inertia of the receptacle is overcome and said receptacle moves forward the speed of rotation of the wheels will decrease until the speed of movement of the receptacle equals that of the belt.

The use of the wheels *P* is an important feature of my invention, as it permits the starting of the receptacle slowly, and a gradual increase in the speed of movement, so as to prevent any sudden strain upon the parts, tending to cause irregularity in the movement of the same, and also prevents the imparting of a sudden jerk to the receptacle, which would have a tendency to dislodge its contents. In this respect my invention differs materially from rope railways in which the receptacle has a rigid friction-shoe for resting upon the endless rope.

25 In order to stop the receptacle before the same reaches the driving-pulley or carrier-pulley of the endless rope, I use buffers *w*—such, for instance, as shown in Figs. 3 and 5, and by dotted lines in Fig. 2—these buffers

30 being preferably clothed with rubber or other elastic material to prevent jar when the receptacle strikes the same. The wheels *P* of the receptacle ride over the supporting-wheels *I* as the receptacle moves forward, and in order

35 to prevent lateral displacement of the wheels the wheels *P* of the receptacle have flaring grooves, and the supporting-wheels *I* have beveled peripheries adapted to these grooves, both sets of wheels being clothed with rubber

40 or other elastic material, as shown in Figs. 7 and 8, so as to lessen the noise and prevent the jarring of the receptacle when passing the supporting-wheels. The driving and carrier pulleys for the endless rope are also by preference clothed with rubber to reduce the noise.

45 The frames *N* of the receptacle are such as to partly embrace the supporting-wheels, as shown in Fig. 4, and thus prevent the lateral swinging of the receptacle as it passes the supports; and in order to properly center the receptacle as it approaches a supporting-wheel the front ends of two of the stay-rods *m m* are projected and bent outward so as to form a flaring guide, as shown

55 in Fig. 6.

To prevent the wheels of the receptacle from jumping from the supporting-wheels when passing the same, I provide each frame *N* with a plate, *u*, which, by contact with the supporting-pulley *I*, will limit the vertical movement of the frame.

Instead of using the short plates shown in the drawings, a plate extending from one frame to the other may be employed, if desired.

65 It may be advisable in some cases to limit the freedom of movement of the wheels *P* of the receptacle, and in such cases I employ a

friction-spring, *p*, carried by one of the stay-rods *m* and bearing upon the side of the wheel, as shown in Figs. 3, 4, and 6.

If desired, the driving-shaft may have more than one driving-pulley, as shown, for instance, in Fig. 11, these pulleys being at such distance apart that the receptacles traveling on the upper system of ropes will be clear of the lower system.

When it is desired to deflect the endless rope from a straight course, I employ guide-reels *S*, as shown in Figs. 9 and 10, these reels providing a lateral bearing for the rope, and two or more pairs of reels being preferably employed at each turn in order to lessen the angle of deflection.

Although it is preferable to provide each receptacle with two or more supporting-wheels, the receptacles may have but a single central frame and wheel, if desired; or the receptacles might be made in duplex form, with the wheel or wheels between, if desired, as shown in Fig. 12; but it is preferable to provide the receptacle with a frame carrying the wheel or wheels and open on one side for the entrance of the rope, as by this means the center of gravity of the receptacle is directly beneath the rope.

I claim as my invention—

1. The combination of an endless rope and mechanism for driving the same with a receptacle carrying a supporting wheel or wheels adapted to rest upon said rope, as set forth.

2. The combination of the receptacle having a supporting wheel or wheels with the endless rope, its pulleys, and supporting-wheels for said rope, as set forth.

3. The combination of the endless rope and its pulleys with beveled supporting-wheels for the rope and a receptacle having a wheel or wheels grooved for the reception of said supporting-wheels, as set forth.

4. The combination of the endless rope and its pulleys, the rope-supporting wheels having beveled peripheries, and the receptacles having supporting-wheels with grooved peripheries, the peripheries of both sets of wheels being composed of rubber or other elastic material, as set forth.

5. The receptacle having a supporting wheel or wheels and a friction-brake therefor, as specified.

6. The combination of the endless rope, the driving-pulley, the take-up pulley and its yoke, and a tension-rope connected to said yoke and to a windlass, as set forth.

7. The combination of the endless rope, the driving-pulley, the take-up pulley and the yoke, the windlass, the tension-rope, and a spring connected to said rope and to the yoke, as set forth.

8. The combination of the endless rope, the take-up pulley, the supporting-wheels adjacent thereto, and a yoke forming bearings for both the pulley and wheels, as set forth.

9. The combination of the endless rope and its pulleys, the receptacles having supporting-

wheels adapted to the rope, and stops for arresting the receptacles before they reach the pulleys, as set forth.

10. The combination of the endless rope, its 5 pulleys, and supporting-wheels, with receptacles having supporting-wheels for resting upon said rope, and stops whereby the supporting-wheels of the receptacles are prevented from jumping when passing the supporting-wheels 10 of the rope, all substantially as specified.

11. The combination of the endless rope, its 15 pulleys, and supporting-wheels, with receptacles having supporting-wheels, and projecting guide-rods serving to center the receptacle as it approaches the rope-supporting wheels, as set forth.

12. The combination of the endless rope, its pulleys, and supporting-wheels, with receptacles having frames constructed to partially 20 embrace the lower portions of the rope-supporting wheels, as specified.

13. The combination of a driving-shaft, a multiple-grooved driving-pulley thereon, a series of endless belts, each adapted to one of the grooves of the driving-pulley, and a series 25 of outer carrier-pulleys, one for each rope, all substantially as specified.

14. The combination of the endless rope and pulleys at opposite ends of the line with intermediate reels providing a lateral bearing 30 for the rope, each reel consisting of a hub free to turn at all times upon its axial shaft, and having projecting arms, the ends of which form bearings for the rope, all substantially as specified.

In testimony whereof I have signed my name to this specification in the presence of two subscribing witnesses.

WM. R. FOWLER.
